PISTON RING

Ernest C. Norton, Moline, Ill.

Application May 23, 1934, Serial No. 727,049

3 Claims. (Cl. 309—43)

The present invention relates to piston rings of the plural-piece type which are held outwardly in contact with the cylinder wall by resilient means which engages the ring sections in a plurality of 5 points and also engages the piston whereby to cause as nearly an even pressure as possible upon the entire outer cylinder contacting face of the ring. Among the objects of this invention are: to provide a ring of the character indicated 10 which will be easily assembled and held in the piston grooves while the piston is being inserted into the cylinder; to provide an improved construction of ring of the character indicated which readily lends itself to being caused to engage the cylinder wall with a substantially uniform pressure 15 throughout its entire length; to provide a ring of the character indicated in which the external surface wear of the ring is as nearly uniform as it is possible to secure; to provide an improved construction of oil ring; and such further 20 objects, advantages and capabilities as will hereafter appear and as are inherent in the construction disclosed herein. My invention further resides in the combination, construction and arrangement of parts illustrated in the accompanying drawing and, while I have shown 25 therein what is now considered the preferred embodiment of this invention, I desire the same to be understood as illustrative only and not to be interpreted in a limiting sense.

30 In the drawing annexed hereto and forming a part hereof,

Fig. 1 is a plan view showing a ring constructed in accordance with my present invention, the two sections of the ring being slightly spaced and the ring being shown on an enlarged scale;

Fig. 2 is an inside elevational view of one of the ring sections;

Fig. 3 is a fragmentary central sectional view through the structure shown in Fig. 2, taken in a vertical direction;

Fig. 4 is a fragmentary horizontal sectional view through the central part of the structure shown in Fig. 2.

45 Reference will now be made in greater detail to the annexed drawing wherein one embodiment of my present invention is illustrated. The ring sections are denoted by the numeral 1 and the springs which give the necessary tension by the numeral 2. The exterior face of the ring section 1 is provided with a groove 3 which is of substantially uniform depth except at its central portion where, as indicated by the numeral 4, the exterior face of the bridge 5 comes nearly to the 50 exterior cylindrical face of the ring.

A groove 6 of substantially uniform depth is located in the inner face of the ring and is shown as extending diagonally thereof, although this is not, in all cases, essential. The internal and external grooves are connected at intervals by the 5 slots 7 which are cut in from the exterior face of the ring and form openings through which oil may pass from the exterior to the interior face of the ring. These slots are formed in oil rings but are omitted in compression rings.

10 Substantially midway of its length, the spring 2 has a flattened portion 8, the forming of which causes the spring to be expanded laterally so that it will have a tight fit in the groove 6, when pressed therein. This results in the spring 2 being held in place in the groove 6 so that the ring sections are easily assembled in the ring grooves of the piston. Between the slots 7 are bridges 9 which hold the two portions of each ring section spaced a proper distance. As indicated at 15 10, each end of each spring section is curved inwardly so that there shall be no sharp points of the spring engaging the ring and preventing proper motion of one relative to the other.

15 The space between the spring 2 and the walls 25 of the groove 6 is shown in the drawing somewhat exaggerated in order to emphasize the fact that the only place where the spring binds in the groove is where it is flattened at 8. On account 30 of the diagonal arrangement of the groove 6 and spring 2, there is greater space and freedom of motion for oil through the slots 7 than if the spring groove were placed centrally throughout the length of the inner wall of the ring. The 35 bent central portion of the spring 2 bears against the bridge 5, while its bent ends 10 bear against the end portions of the ring section. The outward pressure of the piston on the spring 2 is radial of the piston and substantially midway of 40 the parts of the spring, that is, in a radial direction through the bridges 9. Therefore, the pressure of the spring against the ring sections is such as to keep a substantially uniform unit area 45 pressure between the inner face of the cylinder and the exterior face of the ring. Consequently, there is substantially uniform wear of the ring, as has been shown by extensive use of these rings in automobiles subjected to extreme conditions of use.

50 It is of course understood that the specific description of structure set forth above may be departed from without departing from the spirit of my invention as set forth in this specification and the appended claims.

Having now described my invention, I claim:

1. In a plural-piece piston ring, a ring segment having internal and external grooves and slots cut through the body of the ring and connecting the internal and external grooves and leaving narrow bridges connecting the portions of the ring body at the two sides of the slots, a bridge substantially centrally of the ring segment serving as an abutment for a spring, and a spring having its ends and its central portion in the internal groove of the ring, the central portion of the spring pressing against the central bridge.

2. A structure as defined by claim 1 in which the central portion of the spring is secured tightly in the groove so that the spring and ring segment will be normally held in assembled relation.

3. A plural-piece piston ring having internal and external grooves and having slots cut through the body of the ring and connecting the internal and external grooves, the internal groove being cut diagonally so that the ends of the internal groove in any ring segment are adjacent opposite lateral faces of the ring segment.

ERNEST C. NORTON.
